UNITED STATES PATENT OFFICE

ALBERT G. PETERKIN, JR., OF BRYN MAWR, PENNSYLVANIA, ASSIGNOR TO THE ATLANTIC REFINING COMPANY, OF PHILADELPHIA, PENNSYLVANIA, A CORPORATION OF PENNSYLVANIA

REFINING HYDROCARBON OILS

Application filed December 4, 1928. Serial No. 323,690.

My invention relates to improvements in refining hydrocarbon oils, and particularly to an improved process for the removal of certain objectionable properties from petroleum distillates, either cracked or uncracked.

Some petroleum distillates, especially those from crude oils which have a high sulphur content, contain objectionable compounds, the greater portion of which are believed to be mercaptans, which impart to the distillates a disagreeable odor and prevent them from meeting certain standard specifications, such, for example, as the requirement that they shall react "sweet" to the "doctor test" described in Technical Paper No. 323-B of the Bureau of Mines.

My invention contemplates the treatment of such distillates as above described, and especially those containing sulphur in the form of mercaptans, to improve their odor and render them "sweet" to the "doctor test".

In accordance with my invention petroleum distillates of an objectionable character as aforesaid are treated with a suitable refining agent or refining agent of such character that it may be revivified, or maintained in or brought to an active state, by bringing it into contact with a suitable element or material, as oxygen or oxygen-containing gas. Such refining agent, for example, may be cupric chloride, lead compounds, such as lead sulphide suspended in sodium hydroxide solution, mercuric chloride, or the like; but it shall be understood that my invention is not to be limited to these particular refining agents, for any equivalent may be utilized.

Further, in accordance with my invention, oxygen is added to the portion of the gas which remains after the oxygen-containing gas has been in contact with the refining agent, whereupon the gas is again circulated through the system to revivify the refining agent.

One of the advantages of my invention is the practical elimination of loss of distillate in the form of vapors. Such loss is one of the decidedly objectionable features of prior processes which include revivification of the refining agent by air blowing or the like, and in which a stream of gas is passed into and

out of the system with the consequent loss of distillate carried off as vapors by the gas.

In carrying out my process, a given amount of air or other suitable oxygen-containing gas is introduced into a system closed, insofar as the circulation of the air or gas is concerned, impure distillate is continuously introduced into the system, and a refined distillate is continuously withdrawn therefrom. During the passage of the distillate through the system it is treated with a suitable reagent or refining agent, as for example, cupric chloride in aqueous solution. The refining agent is revivified, maintained in or brought to an active state either continuously or intermittently by the oxygen content of the air or other suitable gas. When the oxygen content or a portion thereof has been expended in the revivification or reactivation of the refining agent, the air or gas is reoxygenated or brought to a suitable oxygen content by the addition of oxygen thereto, either in a portion of the system substantially free from the refining agent, or in that portion of the system in which the gas is in direct contact with the refining agent. In this way portions of the gas originally introduced into the system may be used indefinitely as a carrying medium whereby oxygen is applied to the refining agent for the purpose of revivifying it. By such procedure there is eliminated the loss of distillate normally resulting when a stream of gas is continuously passed into and out of the system.

The accompanying drawings illustrate more or less diagrammatically and partly in section, apparatus typical of that which may be used in processes contemplated by my invention.

Fig. 1 illustrates one of the systems or forms of apparatus for carrying out a process embodying my invention.

Fig. 2 illustrates a modified system or form of apparatus which may be utilized in carrying out a further process comprehended by my invention.

Referring to Fig. 1, the oil to be treated is delivered through pipe 1 to the pump M, which delivers it in a continuous stream and at suitable pressure into the reaction cham-

ber A, where the oil is brought into contact with a stream of a suitable reagent or refining agent, as for example, cupric chloride in aqueous solution, introduced into the chamber A through the pipe 5, and with an oxygen-containing gas introduced through the pipe 4. In passing through the chamber, the oil, refining agent and gas are intimately commingled so that substantially complete reaction is effected. From the reaction chamber A, the mixture is passed through the pipe 2 into the settling chamber B, whereupon the oil and refining agent separate into layers and the unused or residual portion of the gas passes to the top of the chamber. The oil separates as the upper layer and is withdrawn from the chamber through the valve controlled pipe 3 and run into a storage tank or otherwise suitably disposed of. The refining agent, which due to its continuous contact with the oxygen-containing gas throughout its passage through the reaction chamber, has been constantly maintained in an active condition, forms the lower layer in said chamber, and is withdrawn through the pipe 5, whereupon it is again passed by means of pump Q into and through the reaction chamber A, where it is brought into contact with further portions of the untreated oil.

The gas which collects in the upper part of chamber B, is that portion of the gas introduced into the reaction chamber A which did not react with or was not used in maintaining the refining agent in an active state, and its oxygen content is therefore relatively low as compared with that of the gas introduced into the chamber A. This gas is withdrawn from the chamber B through pipe 4 and again circulated by pump P into chamber A. During its passage from chamber B to chamber A oxygen is added thereto through the valve controlled inlet pipe 6 to replace that used in maintaining the refining agent in an active condition during the previous passage of the gas through the chamber A.

It will thus be seen that a system is provided wherein a continuous stream of oil may be treated, using a given amount of refining agent and a given quantity of gas, each of which may be recirculated, said quantity of gas acting as a medium by which oxygen is carried into treating relation with the refining agent. Under ideal operating conditions there is introduced into the system only amounts of oxygen sufficient to replace the oxygen used up or chemically reacting to revivify the refining agent.

A system somewhat analogous to the system just described is shown in Fig. 2. In this system at least partial revivification of the refining agent is effected by bringing the spent refining agent into contact or treating relation with the oxygen-containing gas while isolated from the oil, as in a chamber

substantially free from the oil or distillate undergoing treatment.

Referring to Fig. 2, the untreated oil is pumped through pipe 11 by the pump N into the reaction chamber C. Refining agent is introduced into the chamber through the pipe 17 and in passing through the chamber the oil and refining agent are intimately mixed so that complete reaction therebetween may take place. Spent or partially spent gas is also introduced through the pipe 17 into the reaction chamber along with the refining agent, as will hereinafter appear.

The intimately commingled oil, refining agent and gas pass from the chamber C through the pipe 12 into the settling chamber D where separation of the oil and refining agent into layers is effected, the gas passing to and collecting in the upper portion of the chamber. The treated oil forming the upper liquid layer is withdrawn from the system through the valve controlled pipe 13 and the spent refining agent which forms the bottom layer is withdrawn through the pipe 15 and passed by pump S into and through the revivifying chamber E.

The spent or partially spent gas collecting in the top of chamber D is withdrawn through pipe 14 and by means of pump R is delivered at suitable pressure into chamber E. During the passage of the gas through the pipe 14, oxygen is added thereto through the valve controlled inlet 16 to replace the oxygen removed from the gas during its previous passage through the system.

In the chamber E, the refining agent which is in a more or less spent condition is brought into intimate contact with the oxygen-containing gas and is revivified or reactivated, thereby using up greater or less amounts of the oxygen content of the gas. The revivified refining agent along with the gas whose oxygen content has been reduced is passed from chamber E through pipe 17 into reaction chamber C as previously stated, whereupon the cycle or series of steps in carrying out the continuous process is repeated.

The process as described in connection with Fig. 2 is of particular advantage in insuring that the refining agent entering the reaction chamber is restored to the proper strength after prior utilization. The reaction between the refining agent and the oil which effects purification of the latter is, in general, a more rapid reaction than that of revivifying the reagent. Therefore, although the purification and revivification may occur simultaneously in the reaction chamber A, Fig. 1, due to insufficient time of contact to complete the revivification, the reagent may become progressively weaker in refining properties upon continued recirculation. This result is avoided by interposing the step of passage through the chamber E, Fig. 2, in which the reagent is re-

stored to substantially its former strength.

Under some conditions it may be desirable to effect revivification entirely in the chamber E and to recirculate the residual gas through the chamber C substantially free from oxygen. Such procedure has the advantages of the agitation in the reaction chamber C effected by the passage of gas therethrough, which results in insuring intimate contact between the liquids and efficient utilization of the refining agent.

When, for example, lead compounds, such as lead sulphide suspended in sodium hydroxide or plumbite solution is used as a refining agent to sweeten hydrocarbon oils containing objectionable sulphur compounds, it is customary to add an auxiliary reagent, particularly elementary sulphur to the reacting mixture. In my process, such auxiliary reagent may be introduced into the system, either admixed with the untreated oil entering at 1 or 11, or through a specially provided inlet, such as valve controlled pipe 3b communicating with chamber B (Fig. 1).

In instances where a refining agent is used which due to the nature of its reaction with other substances present, results in the formation and accumulation of undesirable material or materials within the system, suitable means are provided, as for example, valve controlled pipe 3a communicating with chamber B (Fig. 1), by which such materials may be withdrawn from the system.

The gas introduced through pipe 6 or pipe 16 is preferably substantially solely oxygen, or equivalent, as from a tank or reservoir thereof under pressure. If the oxygen or equivalent introduced is in mixture with other gas, there will accumulate in the system an excess of inert or carrier gas which will have to be drawn off from the system, continuously or at intervals.

It is to be understood that this invention is not to be limited to specific details as set forth herein but is to be considered as covering the processes described and such obvious modifications as may suggest themselves to those skilled in the art.

In the appended claims the term "sweetening agent" is used for brevity to cover refining agents of the type which will react with a sour hydrocarbon oil to sweeten it, and which after effecting sweetening may be revivified, maintained in or brought to an active state by contacting with oxygen. Examples of such agents have been given, but without limiting the invention thereto, since equivalent agents are contemplated by this invention.

What I claim is:

1. A continuous closed cyclic process for treating sour hydrocarbon oil, which comprises passing the oil in a continuous stream through a treating zone, during such passage subjecting the oil to the action of a confined

quantity of sweetening agent capable of reactivation by free oxygen, maintaining the sweetening agent active by contacting it with a confined quantity of gas containing free oxygen, and replacing the oxygen consumed in maintaining the sweetening agent active by adding free oxygen to said gas. 70

2. A continuous closed cyclic process for treating sour hydrocarbon oil, which comprises passing the oil in a continuous stream through a treating zone, during such passage subjecting the oil to the action of a confined stream of sweetening agent capable of reactivation by free oxygen, recirculating said agent into and out of said zone, maintaining the sweetening agent active by contacting it with a confined stream of gas containing free oxygen circulating into and out of contact therewith, and replacing oxygen consumed in maintaining the sweetening agent active by 85 adding free oxygen to said gas.

3. A continuous closed cyclic process for treating sour hydrocarbon oil, which comprises passing the oil in a continuous stream through a treating zone, during such passage 90 subjecting the oil to the action of a confined stream of sweetening agent capable of reactivation by free oxygen, recirculating said agent into and out of said zone, maintaining the sweetening agent active by contacting it 95 with a confined stream of gas containing free oxygen circulating into and out of contact therewith, and replacing oxygen consumed in maintaining the sweetening agent active by adding free oxygen to said gas.

4. A continuous closed cyclic process for treating sour hydrocarbon oil, which comprises passing the oil in a continuous stream through a treating zone, during such passage 105 subjecting the oil to the action of a sweetening agent passing in a continuous stream into said zone, said sweetening agent being capable of reactivation by free oxygen, passing a gas containing free oxygen in a continuous 110 confined stream into said zone to maintain the sweetening agent active, removing the oil, sweetening agent and gas from said zone and separating them, returning the sweetening agent and gas to the treating zone, and adding oxygen to said gas. 115

5. A continuous closed cyclic process for treating sour hydrocarbon oil, which comprises passing the oil in a continuous stream through a treating zone, sweetening the oil 120 during such passage by subjecting it to the action of a confined quantity of sweetening agent said sweetening agent being capable of reactivation by free oxygen, passing in a continuous confined stream into said zone, 125 passing a gas containing free oxygen in a continuous stream into said zone to maintain the sweetening agent active, removing the oil, sweetening agent and gas from said zone and separating them, supplying oxygen to 130

said gas, thereafter intimately commingling the gas and sweetening agent to reactivate the latter, and passing the commingled gas and sweetening agent into the treating zone.

6. A continuous closed cyclic process for treating sour hydrocarbon oil, which comprises passing the oil in a continuous stream through a treating zone, during such passage subjecting the oil to the action of a confined quantity of cupric chloride solution, maintaining the cupric chloride active by contacting it with a confined quantity of gas containing free oxygen, and replacing the oxygen consumed in maintaining the cupric chloride active by adding free oxygen to said gas.

7. A continuous closed cyclic process for treating sour hydrocarbon oil, which comprises passing the oil in a continuous stream through a treating zone, during such passage subjecting the oil to the action of a confined stream of cupric chloride solution recirculating into and out of said zone, maintaining the cupric chloride active by contacting it with a confined stream of gas containing free oxygen circulating into and out of contact therewith, and replacing oxygen consumed in maintaining the cupric chloride active by adding free oxygen to said gas while the latter is out of contact with said agent.

8. A continuous closed cyclic process for treating sour hydrocarbon oil, which comprises passing the oil in a continuous stream through a treating zone, during such passage subjecting the oil to the action of a cupric chloride solution passing in a continuous stream into said zone, passing a gas containing free oxygen in a continuous stream into said zone to maintain the cupric chloride active, removing the oil, cupric chloride solution and gas from said zone and separating them, returning the cupric chloride and gas to the treating zone, and adding oxygen to said gas.

9. A continuous closed cyclic process for treating sour hydrocarbon oil, which comprises passing the oil in a continuous stream through a treating zone, sweetening the oil during such passage by subjecting it to the action of a confined quantity of cupric chloride solution passing in a continuous stream into said zone, passing a gas containing free oxygen in a continuous stream into said zone to maintain the cupric chloride active, removing the oil, cupric chloride solution and gas from said zone and separating them, supplying oxygen to said gas, thereafter intimately commingling the gas and cupric chloride solution to activate the latter, and passing the commingled gas and cupric chloride solution into the treating zone.

ALBERT G. PETERKIN, JR.
